UNITED STATES PATENT OFFICE.

PERLEY RAYMOND WESLEY, OF PROVIDENCE, RHODE ISLAND, ASSIGNOR TO DAVOL RUBBER COMPANY, OF PROVIDENCE, RHODE ISLAND, A CORPORATION OF RHODE ISLAND.

ICE-BAG.

1,322,984.

Specification of Letters Patent. Patented Nov. 25, 1919.

Application filed October 29, 1917. Serial No. 198,999.

To all whom it may concern:

Be it known that I, PERLEY RAYMOND WESLEY, a citizen of the United States, residing at Providence, in the county of Providence and State of Rhode Island, have invented a new and useful Improvement in Ice-Rags, of which the following is a specification.

This invention relates to certain new and useful improvements in ice bags and pertains more particularly to an ice bag for use on the head of the user.

The primary object of the invention is to provide an ice bag which is formed so as 15 to be closely fitted to the head of the user and especially to fit conformably over the crown of the head, and to provide means for fastening the bag so as to hold same securely against accidental movement without passing

20 beneath the chin.

Further, the invention aims to provide means for refilling the bag located at the top thereof so as to assist in holding the bag in position on the head of the user.

25 Further and other objects will be later herein set forth and manifested in the course of the following description.

In the drawings—

Figure 1 is a perspective view of the invention showing the bag in position on the head of a user.

Fig. 2 is a plan view of the invention showing the parts before the securing strap is secured to the anchoring strap, and

35 Fig. 3 is an enlarged detail sectional view of the filling means, on line 3—3 of Fig. 2.

In proceeding in accordance with the invention, a bag 1 preferably of rubber is employed and of somewhat oval form in plan 40 as shown in Fig. 2. The bag has a pair of oppositely located members 2 of strip form, which are formed of elastic rubber; a non-elastic strap 3 bearing a buckle 4, being connected to one of the members 2, while a similar non-elastic strap 5 is connected to the other member 2, and is passed through a loop 6 formed on the lower end of an anchoring strap 7, the latter connected to the bag 1, so as to depend from the rear of the 45 latter and is located at right angles to the

plane in which the straps 3 and 5 are located. The strap 7 engages the back of the head as depicted in Fig. 1.

The filling means consists of a collar 8 which is threaded as shown in Fig. 3 and 55 has an outwardly turned peripheral flange 9 at its top. The bag has a neck 10 which is engaged over the periphery of the threads of the collar 8, and is held in place by an elastic band 11' which acts to closely hold 60 the neck of the bag against the collar so as to form a water tight joint or connection therewith. A gasket 11 seats on the flange and is engaged by a cap 12 that has a depending part 13 threaded into engagement 65 with the interior threads of the collar 8. The lower end of the collar 8 is preferably curled at 14 so as to prevent abrasion of the bag 1, and by virtue of the threads being pressed into the collar it will be apparent 70 that a more effective securement of the bag is obtained as is evident from Fig. 3, in which the band 11' causes the bag to be forced into the undulations of the threads.

The bag is used by placing same on the 75 head of the user in the position shown in Fig. 1, with the filling means facing upwardly, and with the strap 7 depending from the bag at the back of the head, while the straps 3 and 5 pass around the head above 80 the ears and by virtue of the members 2 being elastic, it will be apparent that the straps can be drawn to cause the same to closely and snugly engage about the head, holding the bag securely in place. The bag is tilted 85 slightly toward the face of the user so as to prevent any slippage of the strap 5, and the strap 7, acts to prevent undue tilting or to limit the forward movement of the bag as is believed obvious from Fig. 1.

Having thus described my invention, what I claim as new and desire to secure by Letters Patent is—

An ice bag for head use comprising a 95 seamless, flexible bag body of substantially oval shape adapted to fit over the forward part of the crown of the head in downwardly tilted position above the forehead, oppositely extending elastic members attached to the upper side of the body adjacent its end 100

edges, non-elastic securing straps connected to the elastic members, and a non-elastic anchoring strap attached at one end directly to the body in a different plane from that of 5 the elastic members so as to be disposed on the under side of the body adjacent its rear edge whereby it will lie flat on the head, the opposite end of the anchoring strap connected to one of the securing straps.

In testimony whereof I have signed my name to this specification in the presence of two subscribing witnesses.

P. RAYMOND WESLEY.
